H. E. FOSSENKEMPER.
CHASE LOCK BAR.
APPLICATION FILED OCT. 19, 1914.

1,152,162.

Patented Aug. 31, 1915.

UNITED STATES PATENT OFFICE.

HARRY E. FOSSENKEMPER, OF RICHMOND, INDIANA.

CHASE-LOCK BAR.

1,152,162.

Specification of Letters Patent. Patented Aug. 31, 1915.

Application filed October 19, 1914. Serial No. 867,419.

To all whom it may concern:

Be it known that I, HARRY E. FOSSENKEMPER, a citizen of the United States, residing in the city of Richmond, in the 5 county of Wayne and State of Indiana, have invented a new and useful Chase-Lock Bar for Printing-Presses, of which the following is a full, clear, and comprehensive exposition and specification, being such as will 10 enable others familiar with the art to which it pertains to make and use the same with exactitude.

My invention relates to improvements in printing presses, particularly those having 15 a horizontal bed adapted to move forward and backward carrying a chase of types, and with a cylinder adapted to revolve above the bed and in contact with the bearers or tracks carried by the edges of the bed.

20 This invention relates, more particularly, to the means for securing a chase of types in operative position upon the surface of the bed.

In securing a chase of types on the bed- 25 plate of a press it is customary to fill in the spaces around the chase with furniture, or blocks, and then clamp the chase in place, but this plan is very unsatisfactory, as the blocks are liable to buckle thereby freeing 30 the chase, and also when the chase is small it requires a great number of blocks of furniture to fill in the spaces.

My invention comprises a single space bar which is adjustable at convenient points for- 35 ward and backward within the limits of the face of the bed, whereby the working extent of the face of the bed may be varied according to the size of the chase which it is desired to secure, thereby minimizing the 40 amount of furniture required and also making the chase more secure.

The object of my invention, broadly speaking, is to provide means for locking a chase of types upon the surface of a bed 45 of a printing press, the said means being strong and durable in construction, positive in action, neat and mechanical in appearance, easily operated and controlled, and which can be manufactured and sold at a 50 comparatively low price.

More specifically stated my object is to provide a chase-lock bar for printing presses, the same being adapted to be adjustably secured at any desired point along 55 the length of the bed, and to be detachably connected to the bearers rising from each

side of the bed, whereby the working surface of the bed may be varied in size to accommodate the chase to be secured, thereby dispensing with most of the furniture 60 usually employed in locking the chase in position, also accurately squaring the chase with relation to the bed, making the chase more secure in its operative position, and minimizing the labor required to secure the 65 chase in position on the bed.

Other minor objects and particular advantages of my invention will be made apparent to the expert in the course of the following description, and that which is 70 new will be correlated in the appended claims.

The preferred means for carrying out the principles of my invention in a practical manner is shown in the accompanying draw- 75 ings, in which—

Figure 1 is a front perspective view of a portion of a printing press, showing my invention in connection therewith in operative position, only such portions of the printing 80 press being shown as is necessary for a clear understanding of the application of my invention thereto. Fig. 2 is a plan view of one end portion of the space-bar, as it would appear in locking or operative position. Fig. 3 is a plan view of the other end portion of the space-bar, as it would appear in unlocked or inoperative position. Fig. 4 is a side elevation or edge view of one end 85 portion of the space-bar, as it would appear in inoperative position. Fig. 5 is a longitudinal section of one end portion of the space-bar, showing the plunger in operative position but not locked with relation to the space-bar. And Fig. 6 is a detail view 90 showing a portion of the bed-plate in vertical section, and showing in elevation an inner or opposing face view of one of the bearers.

Similar indices denote like parts throughout the several views.

In order that the construction, the operation, and the application of my invention to a printing press, may be fully understood and appreciated I will now take up a detailed description thereof in which I will set forth the invention as briefly and as comprehensively as I may.

In the drawings letter A denotes the horizontal bed-plate, which is a part of or is 110 carried by the usual body B. The bed-plate is adapted to slide forward and backward

in the frame H of the press, which latter rests upon the floor. Mounted in the frame H of the machine is the revoluble cylinder C, which is located above the bed-plate but is not in contact therewith.

5 Secured on the surface of the bed-plate and rising from the edges thereof are the bearers D and E; and carried by the ends of the cylinder are the rollers F and G which are adapted to revolve on the surfaces of the bearers as the bed-plate moves forward and backward. Attached to the front edge of the bed-plate are a plurality of clamps, as the clamps I and J, which are adapted to be moved forward and backward by the respective screws K and L.

Letter M denotes the chase, which is simply a metal frame adapted to lie flat on the surface of the bed-plate.

20 Letter N denotes the form, or a column of types, from which the printing is made. The form may be locked in the chase M as follows: Located around the inside of the chase are the furniture blocks a, b, c and d; and placed around the form N are the furniture blocks e, f, g and h. Located between the furniture blocks a and e is the quoin O; between the furniture blocks b and f is the quoin P; between the furniture blocks c and g is the quoin Q; and between the furniture blocks d and h is the quoin R. The said quoins being for the purpose of wedging and locking the form in the chase.

35 Letters T and U denote the outer furniture blocks, that is the furniture blocks outside of the chase containing the form.

40 All of the parts above mentioned are of ordinary design and they may be variously changed as desired, as my invention is not to be limited to the particular construction above mentioned.

45 My invention proper comprises a flat metal bar 1, whose length is such as to allow it to fit snugly between the two bearers D and E, as in Fig. 1.

50 Formed into each end of the bar 1 are two cylindrical apertures, or cavities, as the aperture 2 shown most clearly in Fig. 5; and in each of said apertures 2 is located a plunger, as the plungers 3, 4, 5 and 6, which are adapted to turn and to slide in their respective apertures parallel with the length of the bar 1.

55 Located in the bottom portion of each of the apertures 2 is a collapsible helical spring, as the springs 7, 8, 9 and 10, which contact with the inner ends of the respective plungers 3, 4, 5 and 6, and normally force the plungers outward to their limits.

60 Formed in the upper face of the bar 1, over each of the apertures 2, and extending down into, and out through the edge of, the bar even with the lower line of said apertures, are the U-shaped notches 11, 12, 13 and 14. The two side portions of each of

the said notches are at right angles to their plunger, and open out through the edges of the bar, while the third or body portion of each notch is parallel with the plunger.

65 Rigidly secured to the central portion of each plunger 3, 4, 5 and 6, is a stem, as the respective stems 15, 16, 17 and 18. The said stems afford means for manually moving said plungers, and also providing means for locking the plungers in either operative or inoperative position, and they are adapted to be moved in a vertical position in the body portion and to be turned down horizontally in either of the side portions of the respective notches, to secure the plunger in its projected position as in Fig. 2; or in inoperative position as in Fig. 3. The free end portions of said stems project out slightly beyond the edges of the bar as shown, to afford means whereby they may be engaged by one's hand, or by a tool, for turning them up into vertical position, that is to the position shown in Fig. 5.

70 Formed in the inner or opposing faces of the bearers D and E are socket apertures 19 and 20, respectively. The said socket apertures are adapted to receive therein the projected portion of the plungers when the plungers are brought into line therewith.

75 *Modus operandi:* In practice the operation of my invention is very simple,—The furniture block T is first placed on the bed-plate and in contact with the faces of the clamps I and J. The chase, in which the form has been previously locked, is then placed on the bed-plate with its forward edge in contact with the furniture block T. The furniture block U is then placed in contact with the rear edge of the chase. The next operation is to bring my invention into 100 action. This is done by bringing the bar 1 to the rear of the furniture block U and with its ends in contact with the opposing faces of the bearers D and E, but prior thereto all of the plungers should have been drawn 105 back and secured in inoperative position as in Fig. 3. The bar 1 is then slid forward on the bed-plate and against or near the furniture block U and in such position that all of the plungers will each be in alinement with 110 one of the sockets 19 and 20. After the bar is thus located then all of the stems 15, 16, 17 and 18 are then turned up in vertical position, as in Fig. 5, which will permit the plungers to be forced into their respective 115 sockets 19 and 20 by their respective springs. The stems, above referred to, should then be turned down horizontally, as in Fig. 2, which will lock the plungers in operative 120 position, and thereby retain the bar in its proper place. It is now evident that the bar 1 will be securely locked in its adjusted position between the bearers D and E, then by simply tightening the screws K and L the 125 said parts will be pressed against the bar 1, 130

where they will be securely locked in operative position on the bed-plate ready for the operation of printing in the usual manner.

I desire that it be understood that various changes may be made in the details of construction, from that herein shown and described, without departing from the spirit of my invention and without sacrificing any of the advantages thereof.

10 Having now fully shown and described my invention, what I claim and desire to secure by Letters Patent of the United States, is—

1. In combination with a printing press 15 having a flat bed-plate and bearers extending up from the sides of the bed-plate, there being sockets formed in the opposing faces of the bearers, a flat metal bar adapted to extend across the bed-plate with its ends 20 contacting with the opposing faces of the bearers, there being cylindrical apertures extending into each end of the bar, there being U-shaped notches extending down into and out through the edges of said bar 25 and opening into their respective cylindrical apertures, a plunger operative in each of said cylindrical apertures, a spring normally pressing the plunger outward, and a stem extending out from each plunger at 30 right-angles thereto, said stem being adapted to operate in said U-shaped notch of the bar, all substantially as shown and described and for the purposes set forth.

2. In combination with a printing press 35 having a flat bed-plate and bearers extending up from the sides of the bed-plate, there being sockets formed in the opposing faces of the bearers, a bar adapted to extend across between said bearers and having a 40 cylindrical aperture formed in each end and extending longitudinally thereof and registering with the sockets in the bearers, there being a U-shaped notch formed in the upper face of the bar and extending down into 45 said socket with the central portion of said notch parallel with the cylindrical aperture and the sides of said notch extending out horizontally through one edge of the bar, a plunger slidable in said cylindrical aperture, a coil spring located in said cylindrical aperture and normally pressing the plunger outward, a stem extending out at 50 right-angles from the plunger and adapted to travel in the central portion of the notch and adapted to rest in either one of the sides of said notch, all substantially as shown and described.

3. In combination with a printing-press 55 having a bed-plate and bearers extending up from the sides of the bed-plate, there being a row of sockets extending from end to end of the bearers and located horizontally in the opposing faces of the bearers, a movable bar adapted to rest on the bed-plate with its ends in contact with the op-

posing faces of the bearers, there being a cylindrical aperture extending into each end of the bar and each adapted to register with either one of the sockets of the respective bearers, there being a U-shaped notch extending down into and out through the edge of each end portion of the bar with the central portion of each notch opening into and being parallel with its respective cylindrical aperture, a plunger slidable in each cylindrical aperture and adapted to be located entirely in the cylindrical aperture or with its outer portion inserted in one of the sockets of the bearers, a stem extending out at right-angles from each plunger and adapted to travel in the central portion of its notch and to rest in either one of the side portions of its notch to lock the plunger in operative or in inoperative position.

4. In combination with a printing press 85 having a bed-plate and bearers extending up from the sides of the bed-plate, there being sockets formed in the opposing faces of the bearers, a movable bar extending between said bearers, there being two cylindrical apertures extending into each end of the bar and both adapted at one time to register with two of said sockets in the bearers, there being two U-shaped notches 90 formed at each end portion of the bar and each extending down into and out through opposite edges of the bar, the central portion of each notch opens into its respective cylindrical aperture with the end portions of the notches opening out through the edges of the bar, a plunger slidable in each cylindrical aperture, a stem extending out at right angles from each plunger and adapted to travel in the central portion of its notch and adapted to be turned down 95 into the end portions of the notch to lock the plunger in its extended or in its inoperative position, the lengths of said stems being such that when they are turned down they will extend out beyond the edges 100 of the bar.

5. A chase lock bar, comprising a flat bar having cylindrical apertures extending into the ends thereof and parallel therewith, U-shaped notches formed in the surface of the 115 bar, there being one of said notches for each cylindrical aperture and each extending down into the bar, the central portion of each notch extending down into its cylindrical aperture and parallel therewith, the 120 end portions of each notch extending out through the edge of the bar at right-angles to their central portion, plungers each adapted to be entirely inclosed in its respective cylindrical aperture, means for causing 125 the outer portion of each plunger to project out beyond the end of the bar, a stem extending at right angles from each plunger by which the plunger may be turned and moved in and out, the said stem when 130

- turned in vertical position being adapted to move in the central portion of its notch and adapted to be turned down horizontally into either one of the side portions of its notch
- 5 to lock the plunger at either limit of its movement longitudinally of the bar, all substantially as set forth.

In testimony whereof I have hereunto subscribed my name to this specification in the presence of two subscribing witnesses.

HARRY E. FOSSENKEMPER.
